PRINTING CONTROL DEVICE

Clair D. Lake, Binghamton, N. Y., assignor to International Business Machines Corporation, New York, N. Y., a corporation of New York

Application May 10, 1941, Serial No. 392,931

2 Claims. (Cl. 101—93)

This invention relates to printing mechanism and more particularly to the control devices utilized in the positioning of the type bars of a printing tabulating machine of the record card controlled type.

The principal object of the invention is to provide a simpler, more compact type bar control mechanism than has heretofore been found in tabulating machines. In such machines there is provided a row of closely spaced type bars which are concurrently elevated to each pass a number of type elements past a printing position opposite a platen. The bars are each provided with ratchet teeth which move past the toe of a pivoted pawl which is normally latched out of the path of the teeth. When a particular type element is to be selected for printing, magnetic devices are caused to trip the pawl into engagement with the proper tooth on the bar and cause interruption of the bar's upward movement to occur when the selected type element is in printing position. The magnetic devices which are magnets have heretofore been arranged to control the pawls through intermediate connections, all of which imposed a load whose operation required a magnet of size which necessitated what might be termed a staggered arrangement; that is, there has generally been required six rows of magnets arranged in tandem progressively farther away from the pawls to be operated.

A more particular object is to provide a type bar positioning mechanism that is more direct in operation; one that is constructed of a minimum number of parts; one that may be conveniently manufactured, and one that is more simple and accessible for assembly adjustment and repair.

With the present arrangement only two rows of magnets are required to control the same number of pawls with the same spacing between the pawls. The rows of magnets are one above the other, so that both are the same distance from the pawls and can act directly thereupon without the necessity of intervening connections. Simplification is thus obtained with a considerable saving of parts and effort, together with a further saving of space in the machine for the accommodation of the devices.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a central section through the magnet and stop pawl unit showing its relation to the reciprocating type bar.

5 Fig. 2 is a section taken on lines 2—2 of Fig. 1, showing the spacing relationship of the parts.

Fig. 3 is a section taken on lines 3—3 of Fig. 2.

Fig. 4 is a view looking in the direction of lines 4—4 of Fig. 1.

10 The type of machine to which the present invention is applied is best shown in Patent 2,042,324, granted to J. R. Peirce on May 26, 1936, wherein the print magnet controlling devices are shown in Fig. 3.

15 As in such machine, the type bars 10 (Fig. 1) are reciprocated by well known controlling cams in synchronism with the passage of perforated record cards past a row of so-called sensing brushes. The upper end of bar 10 carries a plurality of horizontally slideable type elements 11 which pass a platen 12 in succession as the bar rises. Teeth 13 are cut in the bar and so located that they pass the toe of a pawl 14 in succession as corresponding elements 11 reach the

20 printing position. Pawls 14, of which there is one for each bar 10, are pivotally carried and spaced apart on a rod 15 supported by brackets 16 attached to a rectangular cross bar 17. Each pawl is normally urged in a clockwise direction by a spring 18 anchored to a plate 19 and is held in the position shown by the engagement of a horizontal arm of the pawl with the lower edge of a notch in either an upper or lower armature 20 of a magnet 21. The arrangement 25 is such that alternate pawls 14 latch on the upper armatures 20, while the intermediate pawls latch on the lower armatures.

30 The armatures are pivoted at their outer ends and spaced by combs 22 as shown in Fig. 2, 40 while springs 23 serve to hold them rocked away from their magnets 21 against a stop plate 24 which is secured to cross bar 17. The magnets are provided with flat cores and so spaced that the distance between the centers of two adjacent magnets is twice the distance between the centers of two adjacent pawls, thereby enabling the total number of magnets required to be arranged in two rows offset laterally by one pawl spacing.

45 The magnets are supported by a U-shaped member 25 which also carries a U-shaped armature stopping member 26 against which the armatures strike when attracted by their magnets 21. On one side of member 25 is a plate 27 50 of insulating material in which are embedded

55

individual contactors 28 wired to their respective magnets 21. A single contactor 29 lying intermediate the two rows of contactors 28 is wired to each of the magnets.

Behind plate 27 is a frame 30 into which there is slidably insertible an insulating plate 31 provided with a finger grip 32 and which, when inserted, is held in place by screws 33. In plate 31 are embedded plug jacks 34 whose extending blades make contact with the contactors 28 and 29. The jacks are configured to have connecting wires inserted therein for completing circuits through the magnets. On a stud 35 (Fig. 2) concentric with rod 15 is pivoted a bail 36 (see Fig. 3) normally biased against a fixed eccentrically adjustable stop pin 38. Both stud 35 and pin 38 are carried by brackets 39 (one at each end of the unit) attached to cross bar 17. Pivoted to arm 40 of bail 36 is a link 41 which has pin and slot connection 42 with a bail 43 pivoted at 44 to brackets 39 and having a spring 37 which serves to bias the bail 36 clockwise. A spring 45 between bail 43 and arm 40 of bail 36 serves to bias bail 43 clockwise, but its tension is less than that of spring 37. Bail 36 extends beneath all the horizontal arms of pawls 14 and bail 43 extends behind all the armatures 20.

When bail 36 is rocked counterclockwise as will presently be explained, it restores all tripped pawls 14 and, when the play in the slot of link 41 is taken up, spring 45 rocks bail 43 to move all attracted armatures into reengagement with their restored pawls 14. The means for rocking bail 36 is a lever 46 (Fig. 1) pivoted at 47 and having a link connection 48 with a follower lever 49 pivoted at 50. On a machine shaft 51 is a roller arm 52 which, at the proper time in the operation of the machine which is generally just

before the type bars 10 are moved downwardly, strikes lever 49 to restore the pawls 14 and armatures 20 through the connections specified.

It is to be noted that energization of any magnet 21 attracts its armature 20 and directly releases the related pawl 14 and that this action is the same for all magnets, so that all do the same amount of work through the same distances and the power required of each magnet is the same.

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is:

1. In a printing machine, a plurality of spaced type bars arranged side by side to slidably touch one another, a stopping pawl for each bar, said pawls being arranged in a single row, two rows of magnets, an armature for each magnet having a latching edge directly engaging a related one of the pawls, said latching edges lying along a single line and said magnets being spaced a distance equal to twice the spacing of the pawls and related type bars.

2. The invention set forth in claim 1 in which the cores of the magnets are rectangular in cross-section and the magnets in one row are offset one-half their spacing with respect to the magnets in the second row.

CLAIR D. LAKE.
